C. H. SMITH & G. D. WALKER,
VELOCIPED.

No. 91,682.

Patented June 22, 1869.

United States Patent Office.

CHARLES H. SMITH AND GEORGE D. WALKER, OF BROOKLYN,
NEW YORK.

Letters Patent No. 91,682, dated June 22, 1869.

IMPROVEMENT IN VELOCIPEDES.

The Schedule referred to in these Letters Patent and making part of the same.

To all whom it may concern:

Be it known that we, CHARLES H. SMITH and GEORGE D. WALKER, of Brooklyn, in the county of Kings, and State of New York, have invented certain new and useful Improvements in Velocipedes; and we do hereby declare the following to be a full, clear, and exact description of the said invention, reference being had to the annexed drawing, making part of this specification, wherein—

Figure 1 is a side elevation of a two-wheeled velocipede.

Figure 2 is a vertical section of the front post and steering-mechanism.

Figure 3 is a similar view of a modification of said parts.

Figure 4 is a cross-section at the line $x x$ of fig. 2.

Figure 5 represents a modification of the reach and jaws for the rear wheel.

Similar marks of reference denote the same parts.

The object of this invention is to render the vehicle known as the velocipede better fitted for riding over rough roads or pavements, by taking the jolts from slight obstructions upon springs, and spending their force before they reach the seat or steering-handle, thus making the exercise more agreeable and less fatiguing to the rider.

The nature of this invention consists—

First, in applying a spiral or other spring below the steering-handle, so that any jolt from passing over an obstruction, in passing up the steering-post, is taken by the spring, the handle giving at the moment, and coming back to place by the return of the spring, (the handle not being rigidly attached to the steering-post of the jaws of the front wheel,) the handle resting upon said spring, and fitted to slide upon said steering-post, but, at the same time, always being available for steering.

Second, in resting the perch, where it connects with the supports of the front and rear wheel, upon springs, the parts being constructed so as to exclude dirt, so that these springs perform for the perch what the spring in the first part of our invention does for the handle, viz, neutralizing the slight jar and concussion which result from riding over even comparatively smooth pavements, which jarring the ordinary velocipede communicates to the rider, paralyzing the arms and posterior parts of the person after a short time; and, dirt and dust being excluded from the bearings of the perch, a large amount of friction is avoided.

In the drawing—

a represents the front, and *b*, the rear wheel of an ordinary two-wheel velocipede; and we here remark that our invention is not confined in its application to any particular kind of velocipede, but we propose to

apply it, wherever available, on that class of vehicles.

c is the handle;

d, the sleeve, which encircles the steering-post *g*, and forms a support for it; and

e are the forks, which have on them the bearings, *s*, for the front wheel.

The steering-post *g*, which is connected to the forks *e*, terminates at its top as an exterior flange, *l*, which, resting upon the sleeve *d*, forms the bearing-support for the forks *e* and front wheel.

In this post *g*, we form a square or polygonal hole, *i*, extending from the top down to about half the distance to the reach or perch *h*; and this post *g*, instead of, as usually, terminating in a screw for the handle and holding-nut, presents a broad, flat surface, with the hole *i* in it, in which is inserted the square or polygonal rod *k*, which has, on its upper end, the handle *c*, fastened to it in any convenient manner; so that, as the handle is turned, the rod *k* and post *g* are also turned, to steer the velocipede.

This rod *k* extends nearly to the bottom of the hole *i*, and rises above the post *g* high enough to bring the handle to a convenient position for steering; and said handle is held up to its place by a spiral spring, *m*, (or a rubber ring around the rod *k* might be used,) which spring rests upon the flange *l*, of the top of the steering-post *g*, and takes under the hub of the steering-arm *e*.

It will thus be seen that the steering-arm, although not rigidly connected with the steering-post, controls its movements, and any jolt from the wheel communicated to said post is not felt by the hands grasping the handle, the spring *m* giving, and allowing the rod to sink deeper into the hole *i*, and return. *g* the parts immediately to place.

A block of rubber, *t*, is placed at the bottom of the hole *i*, so that, in case the rod *k* should be brought too far down, it would not strike the metal of the post *g*.

In fig. 3, we have shown a modification of this construction, the handle *c* fitting upon the rod *k*, which rod slides in the square hole, *i*, in the sleeve *d*, and the spring *m* is applied between the lower part of the rod *k* and the portion *k'* of the sleeve *d*, said sleeve *d* being connected to the steering-post *g* by the pin *g'*, and the operation of the parts is the same as in fig. 2.

To prevent the rod *k* from coming out accidentally, we form a slot, *3*, in the side of the said rod *k*, and a hole, *4*, in the sleeve *d*.

A screw, *5*, inserted through the hole *4*, connects the rod *k* and post *g*, the slot allowing the necessary vertical play of said rod *k*, and prevents the said rod *k* disconnecting from the steering-post *g*.

The reach *h*, where it rests upon the top of the forks *e*, has formed upon its under side a circular flange, *o*,

forming an inverted cup, somewhat larger than the steering-post, which passes through the centre of said cup.

The upper portion of the forks *e* is formed with a circular flange, *o'*, leaving a recess, *p*, the inner circumference of said flange *o'* being a trifle smaller than the outer circumference of the flange *o*, which sets in said recess, leaving around the post *g* an annular space, for the insertion of the spring *q*, which thus sustains the weight of the front end of the perch, and, consequently, prevents all jolting from the front wheel passing to the seat.

This construction of parts keeps out dust and dirt from the bearing of the reach, which would cause friction in the bearing.

The spring *q* might be a block of rubber.

The rear forks of the perch or reach *h* are formed rounded or square, and, whether the perch is formed as shown in figs. 1 and 5, the application of our invention does not materially differ, the rounded ends *r*, of the reach *h*, entering sockets formed in the hubs *s* on each side of the rear wheel, which hubs also form bearings for the rear wheel.

The ends *r* rest upon springs, *7*, in said sockets, so that the perch or reach is entirely supported upon springs at each of its ends, which springs prevent the jarring that would otherwise be communicated to the perch.

The seat-spring *t* is to be applied to the reach *h* in any desired manner.

Pins 18, upon the rods *r*, entering slots in the sockets *s*, allow the necessary play of the reach, and prevent the disconnection of the parts.

The jaws *e* of the front wheel might be fitted with sockets similar to those on the rear wheel, the jaws *e* entering said sockets, and resting upon springs.

What we claim, and desire to secure by Letters Patent, is—

1. The spring *m*, around the rod *k*, in combination with said rod *k*, formed at its upper end so as to receive the handle *e*, and the steering-post fitted to receive said rod *k*, as set forth.

2. A spring, placed between the steering-arm of a velocipede and the steering-post, for the purposes and substantially as set forth.

3. The perch *h*, formed with the flange *o*, forks *e*, formed with the flange *o'*, spring *q*, and steering-post *g*, combined and arranged substantially as set forth.

4. The perch *h*, sockets *s*, and springs *7*, all combined and arranged substantially as set forth.

In witness whereof, we have hereunto set our signatures, this 13th day of April, A. D. 1869.

CHAS. H. SMITH.
GEO. D. WALKER.
